UNITED STATES PATENT OFFICE.

JOHN VAN BRUNT, OF NEW YORK, N. Y., ASSIGNOR TO COMBUSTION ENGINEERING CORPORATION, OF NEW YORK, N. Y., A CORPORATION OF NEW YORK.

VALVE.

1,345,518.

Specification of Letters Patent.

Patented July 6, 1920.

Application filed March 4, 1919. Serial No. 280,536.

To all whom it may concern:

Be it known that I, JOHN VAN BRUNT, a citizen of the United States, residing at city of New York, county of Queens, and 5 State of New York, have invented certain new and useful Improvements in Valves, of which the following is a full, clear, and exact description.

My invention relates to improvements in 10 valves and has for its object to produce a valve adapted to be used as a throttle valve and adjustable so that when the plug is turned through a given angle the ports of the valve will be more or less completely 15 open according to the adjustment.

Throttle valves in certain relations are 20 automatically actuated by means which turn the plug through a given angle so as to fully open the ports of the valve or fully close the same. There are, however, conditions when 25 it is not desirable to have the valve ports fully opened and the object of my invention is to produce a valve in which the full throw of the plug, so as to bring its passage into 30 the same plane as the valve ports, will not necessarily open those ports to a maximum.

The following is a description of an embodiment of my invention, reference being had to the accompanying drawings, in 35 which,

Figure 1 shows a longitudinal section through the valve casing and its ports with the plug adjusted in one position relatively to its casing;

35 Fig. 2 is a similar section with the plug adjusted so as to be in another position;

Fig. 3 is a transverse section of the valve on the line 3—3, Fig. 1, and

40 Fig. 4 is a similar transverse section with the plug moved axially to partially close the ports.

Referring more particularly to the drawings, 1 is a valve casing having a cylindrical bore. It is provided with nipples 2—2' for 45 the pipes 3—3' leading from the ports 4—4'. 5—5' are caps for the casing and 6 is a cylindrical valve plug within the casing, having a transverse passage 6'. This valve plug is provided at one end with a square recess 7', 50 in which fits the squared end 7 of an actuating member, the shank 8 of which extends through the cap 5 and is provided with an operating lever 9. 10 is an adjusting member being screw-threaded so as to engage

internal screw-threads 11 upon the lower 55 cap and having a head 12 swiveled to the valve plug so that the plug is free to turn relatively to the adjusting member.

When the parts are in the position shown in Figs. 1 and 3, the actuating member 8 60 being turned so as to align the passage 6' with the ports 4—4' and cause them to fully register therewith, the valve ports will be 65 fully opened. If, however, it is desired that the passage through the valve shall not be 70 at its maximum when the lever 9 is in the position shown, the adjusting member 10 is 75 actuated so that the plug 6 is drawn downward so that the passage 6' can not be made to fully register with the ports 4—4', being 80 moved out of the transverse plane passing through the ports 4—4'. In this way the opening through the valve may be made as much smaller as desired when the lever 9 is turned to the position corresponding to the 85 maximum. This longitudinal shifting of the valve plug is permitted by the sliding engagement of the angular portion 7 with the socket 7' (Fig. 2) in the plug. By this means the valve plug can be adjusted so as 90 to close the opening through the valve to any desired degree, thus reducing the opening through the valve corresponding to the maximum throw of the actuating lever, so 95 that the opening through the valve can be 100 made greater or less as desired for any given angular movement of the plug.

When such a valve is used for controlling an engine it can be adjusted so that the maximum speed of the engine will not be 90 reached until the operating lever is moved through its entire range or the valve can be 95 adjusted so that a speed below the maximum will be reached only when the operating lever is moved through its entire range. When once adjusted the opening and closing of the valve in practice will be done entirely by the lever rotating the plug.

As will be evident to those skilled in the art, my invention permits of various modifications without departing from the spirit thereof or the scope of the appended claims.

What I claim is:

1. An adjustable throttle valve comprising a casing having a cylindrical bore, an inlet port and a discharge port on opposite sides thereof and end caps, a cylindrical plug longitudinally movable in said bore 105

- and having a passage extending diametrically through the same and adapted to register with said ports as said plug is revolved, means for adjusting said plug axially so as to move said passage more or less out of the transverse plane passing through said ports and holding it in such adjusted position, and means for rotating said plug when so adjusted and held.
- 10 2. An adjustable throttle valve comprising a casing having a cylindrical bore, an inlet port and a discharge port on opposite sides thereof and end caps, a cylindrical plug longitudinally movable in said bore and having a passage extending diametrically through the same and adapted to register with said ports as said plug is revolved, an adjusting screw swiveled to said plug and engaging stationary screw-threads, and an actuating member passing through the other

cap and connected with said plug so as to rotate therewith.

15 3. An adjustable throttle valve comprising a casing having a cylindrical bore, an inlet port and a discharge port on opposite sides of said casing and end caps, a cylindrical plug longitudinally movable in said bore and having a passage extending diametrically through the same and adapted to register with said ports as said plug is revolved, an adjusting screw swiveled to said plug and engaging stationary screw-threads, and an actuating member passing through the other cap and connected with said plug so as to rotate therewith, said actuating member having one end extending into said plug and making a sliding engagement therewith.

JOHN VAN BRUNT.
